United States Patent Office

Des. 188,342
Patented July 5, 1960

188,342

DRAWER KNOB AND THE LIKE

Benjamin S. Faber, New York, N.Y., assignor to Penn-Akron Corporation, a corporation of Delaware

Filed July 15, 1959, Ser. No. 56,785

Term of patent 14 years

(Cl. D50—3)

FIG. 1

FIG. 2

FIG. 3

Fig. 1 is a top perspective view of a drawer knob, showing my new design.

Fig. 2 is a front elevational view thereof.

Fig. 3 is a rear perspective view thereof.

I claim:

The ornamental design for a drawer knob and the like, as shown.
